UNITED STATES PATENT OFFICE

2,391,441

DRYING RAW ORGANIC MATERIALS

John M. Baer, Chicago, Ill., assignor to The
Guardite Corporation, a corporation of Illinois

Application November 8, 1943, Serial No. 509,481

3 Claims. (Cl. 34—15)

This invention relates to a method of drying raw organic materials and primarily fruits, vegetables, and the like, containing a major proportion of water.

The present invention relates to a method of drying predominantly watery products, while maintaining the product stable against reoxidation and uniform in its characteristics. Treatment according to this process in some instances has been found to leave a considerably higher vitamin content as, for example, vitamin C in potatoes than occurs with other methods.

In carrying out the process the product is cut into small pieces, preferably cubes about $\frac{1}{4}$ inch in cross-section or slices not more than $\frac{1}{8}$ inch thick. These are promptly subjected to a vacuum under which air is withdrawn therefrom. They are then heated by means of steam coils or other source of heat while maintaining the vacuum until a substantial portion of the water has been removed. Thereafter the vacuum is increased progressively until the desired amount of drying has occurred. During the drying process the product is kept at a low temperature, preferably below 120° F., until the final stages of the drying operation. During these last stages the temperature of the product is relatively unimportant and it may be heated considerably higher without detrimental effect.

In carrying out the operation it is preferred to use a vacuum at least as high as 730 mm.—that is, under an absolute pressure of 30 mm. or below. In practical operations an absolute pressure of 20 to 25 mm. has been found desirable for the initial drying operations.

In some operations it may be desirable to employ higher pressures but in all cases it is preferred to maintain the pressure below 100 mm. of mercury and preferably one not substantially above 60 mm. In such cases the temperature allowable may also be increased by adding to 100° F. the pressure in millimeters; that is, at 60 mm. pressure the maximum temperature should be below 160° F. Similarly, the difference between the temperature of the product and the temperature of the steam, which, at 30 mm. should be from 30° to 45° F., may be correspondingly increased so that at 60 mm. it is from 60° to 90° F.

The drying chamber may be supplied with heat through steam coils arranged inside it or by radiant energy or by superheated steam.

The invention is illustrated diagrammatically in the drawing. The vegetable product 10 in the form of small slices or particles is placed upon a foraminous support 11 in close proximity to a

source of radiant energy 12 which may be maintained above and below the product. In the drawing this is illustrated as steam coils, and a connection 13 to the boiler having return connection 14 are indicated. Additional energy may be supplied by superheated steam as indicated by the manifold 15 supplied with a number of vents 16. A connection 17 is also supplied leading to the vacuum pump. Appropriate means are provided for measuring the temperature in the coils 12 in the chamber 18 and so far as possible in the product. The thermocouple 19 is shown as indicating the temperature in the chamber, a thermocouple 20 as indicating the temperature in the coils, and a thermocouple 21 as indicating the temperature in the product.

It is to be understood that this illustration is diagrammatical only in order to illustrate the process described herein. Thus the food product 20 may be supplied and removed continuously or in batches. The source may be steam or other radiant energy and may or may not be supplemented by superheated steam. The thermocouples will in general be supplied at various points throughout the system to obtain a composite temperature.

It has been found that it is difficult to measure accurately the temperature of the product itself undergoing treatment, and that a control based on measuring a predetermined temperature in the product is difficult to apply. It has also been found relatively unimportant how hot the source of heat is, as for example the steam coils. A satisfactory control, however, may be established by correlating the temperature of the chamber itself to the pressure maintained therein. This may be accomplished either by comparison of the temperature of the chamber with the pressure, or by comparison of the temperature of the chamber with the roughly observed temperature of the product undergoing treatment.

Appropriate readings may be taken by inserting thermocouples within the product which will give a reading satisfactory for the present purposes. The temperature of the atmosphere should be taken in such a way as to shield the temperature recording means so far as possible from the effects of the radiant heat.

For example, using a pressure of 20 to 25 mm. of mercury, the temperature inside the chamber should rapidly be brought to a peak below 150° F. and preferably below 135° F., and should be maintained in this range throughout the drying operation even as the pressure is progressively reduced in the latter stages. At the same time the product should be maintained below 120° F.

and preferably below 100° F. during the large bulk of the drying operation. During the latter stages, however, the product temperature may go above that of the chamber.

For example, using raw potatoes cut in $\frac{1}{4}$ inch cubes, the cubed potatoes were placed in a vacuum chamber and subjected to an absolute pressure of about 25 mm. The chamber was heated by steam coils to which steam was supplied under an original pressure of 65 lbs. During the operation the pressure was gradually reduced, and during the latter stages was cut off entirely, the pipes themselves, however, having a residual heat content sufficient to complete the drying. By the time that the chamber pressure had been reduced to 25 mm., the temperature of the chamber was 157° F. and the temperature of the product was approximately 80° F. The chamber temperature, however, rapidly fell to less than 145° F. At the same time the pressure was slowly reduced and by the time it had fallen to 21 mm., the temperature of the product was about 100° F., and the chamber temperature about 132° F.

At this time the greater portion of the water had been removed and the resulting product was dry enough so that the vapor pressure of the water therein was markedly lower. The pressure in the chamber was then reduced progressively until it had fallen to 2.5 mm., during which time the temperature in the chamber likewise fell to around 126° F. On the other hand, the temperature of the product rose to approximately 140° F.

The original potatoes lost approximately 82% of their weight in the drying operation and the final material was a white light-colored material which took up water readily upon immersion, was uniform in its characteristics, and did not discolor upon rewetting. The product had all of the culinary characteristics of raw potatoes and had a high vitamin C content.

Similar operations may be carried out on cabbage, carrots, onions, fruits and other predominantly aqueous vegetable materials.

For example, carrots sliced to $\frac{1}{8}$ inch in thickness were placed in a chamber and the pressure reduced to 23.5 mm., at which time the chamber temperature was 182° F. and the carrot temperature about 76° F. By the time that the carrot temperature had risen to 80° F., the temperature of the chamber had fallen to approximately 130° F. and the pressure to 20 mm. This ratio of temperature and pressure was maintained until the temperature of the carrots began to rise markedly, indicating substantial drying of the product. The pressure was then reduced progressively to as little as 1 mm., and the temperature of the chamber dropped to 116° F. In the meantime the temperature of the carrots rose to about 140° F.

The resulting product was dry, light, and reabsorbed water readily. When rewetted it had the characteristics of the raw carrot. The product lost approximately 86% of its weight during the drying operation.

The chamber temperature may be controlled by adjustment of the rate of evacuation, i. e., the pressure, and by the rate of supply of heat to the coils.

The atmosphere of steam referred to in the claims hereof may be produced by water evaporated from the product under treatment or by supplying steam from an outside source.

Very effective results have been obtained upon potatoes, meat, vegetables and mixtures of meat and vegetables at pressures of 57 mm.

This application is a continuation-in-part of my co-pending application Serial No. 412,201, filed September 24, 1941.

15 The foregoing detailed description has been given for clearness of understanding only, and no unnecessary limitations should be understood therefrom.

What I claim as new, and desire to secure by Letters Patent, is:

1. In the drying of cellular organic products naturally containing a large percentage of moisture, the steps of subjecting the product in small particles in thin layers in an enclosed chamber forming a drying zone to a reduced pressure in an atmosphere of steam substantially free from air, supplying heat to the product from a source of radiant energy in the chamber close to the product having a temperature within the drying zone markedly in excess of the temperature of saturated steam under the prevailing reduced pressure in the chamber, maintaining the product at a temperature of approximately 100° to 120° F. during the greater part of the drying operation, 20 and maintaining the chamber temperature during the same time at 30° to 45° F. above the temperature of the product.

2. In the drying of cellular organic products naturally containing a large percentage of moisture, the steps of subjecting the product in small particles in thin layers in an enclosed chamber forming a drying zone to a reduced pressure below 100 mm. of mercury in an atmosphere of steam substantially free from air, supplying heat to the product from a source of radiant energy in the chamber close to the product having a temperature within the drying zone markedly in excess of the temperature of saturated steam under the prevailing reduced pressure in the chamber, maintaining the product at a temperature between approximately 100° F. and 100° F. plus the pressure in millimeters of mercury maintained on the product during the greater part of the drying operation, and maintaining the chamber temperature during the same time at a temperature in degrees Fahrenheit higher than the temperature of the product by at least one to one and one-half times the pressure of the atmosphere within the chamber as measured in millimeters of mercury.

3. The method as set forth in claim 2, in which the pressure is approximately 60 mm. of mercury.

JOHN M. BAER.
